UNITED STATES PATENT OFFICE.

FURMAN D. SPEAR, OF NEW YORK, N. Y., ASSIGNOR TO ARMSPEAR MANUFACTURING COMPANY, OF NEW YORK, N. Y., A CORPORATION OF NEW YORK.

LAMP.

1,320,346.

Specification of Letters Patent. Patented Oct. 28, 1919.

Application filed February 5, 1919. Serial No. 275,086.

To all whom it may concern:

Be it known that I, FURMAN D. SPEAR, a citizen of the United States of America, residing at New York, New York, have invented a new and useful Lamp, of which the following is a specification.

The main object of my invention is to increase the spread of light from a signal lamp without decreasing its luminosity, particularly of the "Marker" type.

In the preferred form the invention contemplates the use of an attachment which may be applied to a signal lamp and which attachment is in the form of a clamp having an outwardly flaring rim carrying the glass.

Figure 1 is a side view showing a lamp embodying the improvements of my invention.

Fig. 2 is a vertical sectional view on a larger scale showing the goggle or lens attachment.

Fig. 3 is a perspective view of one of the attachment parts.

The main body 5 of the lamp may be of standard size and provided with a fixed goggle 6 which projects laterally from the body. The attachment 7 is suitably secured to this goggle and in turn carries the lens or glass 8, which is materially larger in diameter than the goggle 6. The attachment 7 is preferably formed of two parts as shown in Fig. 3, the lower part as indicated by reference 7' is similar to the upper part 7. For convenience in manufacture and assembling the attachment has a flange 9 which may be notched and yieldingly engage the goggle 6. Each part of the attachment has lugs 10-10 and the lugs of the two parts are adapted to be secured together by bolts such as 11 passed through the lugs, so that the two parts are clamped on the goggle 6. Preferably the outer end of the goggle 6 is flared as at 6' so as to afford a better seat for the attachment. A grooved band 12 is provided for securing the lens to the outer rim 13 of the attachment. The two ends of the band may be clamped together by a bolt 14 and a suitable yielding packing 15 may be used to afford a yielding seat for the rim of the lens against the attachment.

By this construction it will be noted that more of the rays of light may be utilized and a wider angle of dispersion is provided.

In the preferred form of lamp the body is preferably formed of an upper part 5 and a lower part 5' with flanges such as 16 and 17 secured together by bolts 11 and 11' so that the parts may be more easily made and assembled and so that the parts will be interchangeable. By the construction herein disclosed, the attachment may be secured by the same bolts as those employed to fasten the upper and lower parts of the body of the lamp together. I do not wish however to be limited to this specific form of construction.

By this means I am enabled to produce a standard signal lamp and to retain all the advantages of standardization, at the same time making it possible to utilize therewith lenses of different sizes without disturbance or injury to the standard parts.

I claim:

1. In a lamp construction, a body having an outwardly projecting fixed goggle, an attachment formed in two parts, each part having two rearwardly extending lugs, means for connecting the corresponding lugs to the body at the rear of the fixed goggle and thereby clamping said attachment on said goggle, said attachment having an outwardly flaring rim for carrying the lens.

2. An attachment for a signal lamp comprising two substantially semi-circular flange portions arranged to be detachably engaged with a part of the body of the lamp, each flange portion having an outwardly flaring rim for supporting a lens, each flange portion also having two rearwardly extending lugs at its ends with bolts for connecting said lugs to said body.

3. In a lamp construction, a body having an outwardly projecting fixed flange at one side, an extension goggle comprising two semi-circular flange portions arranged to surround the fixed goggle, lugs projecting rearwardly from said flange portions with means for securing said lugs to the body of the lamp to the rear of the fixed goggle, and a clamping ring for the outer edge of the extension goggle, said flange operating to both hold the lens in place and to assist in holding the two portions of the extension goggle in operative position.

FURMAN D. SPEAR.
